[57] CLAIM

The ornamental design for a winder, as shown and described.

DESCRIPTION

FIG. 1 is an isometric view of a winder showing my design from above and front;
 FIG. 2 is an end elevational view thereof, the same having an identical appearance from its other end;
 FIG. 3 is an enlarged transverse sectional detail view thereof taken upon the plane of the section line 3—3 in FIG. 5;

FIG. 4 is a bottom view thereof;
 FIG. 5 is an elevational view of the rear side thereof;
 FIGS. 6 and 7 are respectively front and rear elevational views of another species of a winder of my design;
 FIGS. 8 and 9 are respectively top and bottom views of the design shown in FIGS. 6 and 7; and,
 FIG. 10 is an end view of the design shown in FIGS. 6—9; the same having an identical appearance from its other end.
